ILLUMINABLE FLAG DISPLAY DEVICE

Donald C. Turner, 66 Highledge Drive, Penfield, N.Y.

Filed Aug. 17, 1959, Ser. No. 57,206

Term of patent 14 years

(Cl. D80—9)

FIG. 3

FIG. 4

Fig. 1 is a perspective view of an illuminable flag display device, showing the new design;

Fig. 2 is a slightly enlarged elevational view of the flag blower and associated parts, showing the side of the blower opposite to the side shown in Fig. 1;

Fig. 3 is a fragmentary side elevational view, on an enlarged scale, of the connection between the flagstaff tube and two lower tubes which support it; and

Fig. 4 is a side elevational view, on the same scale as Fig. 3, illustrating further details of the connection of the parts shown in Fig. 3 to the blower.

The broken line showing of a flag is for illustrative purposes only.

I claim:

The ornamental design for an illuminable flag display device, substantially as shown and described,
